UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

RECORD-STRIP COMPOSING-MACHINE.

1,094,630.

Specification of Letters Patent. Patented Apr. 28, 1914.

Application filed May 21, 1913. Serial No. 769,014.

To all whom it may concern:

Be it known that we, JOHN SELLERS BANCROFT and MAURITZ C. INDAHL, citizens of the United States, residing at Philadelphia, 5 in the county of Philadelphia and State of Pennsylvania, have invented certain new and useful Improvements in Record-Strip Composing-Machines; and we do hereby declare the following to be a full, clear, and 10 exact description of the same, reference being had to the accompanying drawings, forming part of this specification, and to the figures and letters of reference marked thereon.

15 This invention relates to keyboard perforating machines of the class commonly employed for producing the successive signals (each composed of one or more perforations and distinguished by number and 20 relative location) which go to make up the record strips or controllers for type casting and other machines, and it has for its principal object to provide means whereby the justification fraction pertaining to any 25 given line of composition may be applied to any one or more of the individual types included in said line in addition to or in substitution for the normal justifying space types.

30 One of the best known machines of the class referred to is illustrated and described in Patent No. 944405, dated December 28, 1909, wherein the various signals employed are each represented by a separate key, the 35 latter controlling, through permutation devices, those members of a series of punches which by their location coincide with the components of the signal pertaining to the depressed key, while at the same time the 40 measure or value of the produced signals pertaining to the same line are registered by a line measuring mechanism, to aid the operator in ascertaining the justification fraction or the appropriate signal therefor for 45 completing the line.

For convenience the term "type" is hereinafter employed to designate type bodies of predetermined and fixed dimensions, such as characters, points, quads, &c., and in 50 distinction the term "space" is used to signify bodies whose setways dimensions are subject to variation for the purpose of justification.

According to the plan of said patented

machine, the justification signals representing the fractional increase to be applied to each space in the line are formed last, that is to say, after all the type signals for a line have been registered, to the end that when the record strip is fed to the casting or other 55 performing machine in the reverse order, said signals may operate to set or adjust the justification mechanism preliminarily to the production of the type and spaces for the line; and, further, the space signals, *i. e.*, 60 those indicating the spaces to which the justification fraction is to be added, operate in the casting machine to bring into action the previously adjusted justification mechanism, and, at the same time, set or adjust 65 a dimensioning member, *to-wit*, the normal wedge, common to both the normal and justification adjusting devices. In other words the functions of the type and space signals are to select the indicated matrix and set or 70 adjust the normal dimensioning mechanism (normal wedge), and in addition the space signals operate to transfer the dimensioning 75 adjustments from the normal dimensioning devices (normal wedge) to the normal and justification adjusting devices (normal wedge and justification wedges combined), the last named having previously been set 80 by the justification signal. One component of each type signal designates an adjustment 85 of the normal wedge in the casting machine corresponding with the set way measure of the indicated type, and the punch for producing said dimensioning component is coupled with the line measuring mechanism to 90 add its value to the line measure, and one component of the space signal in like manner adjusts the normal wedge of the casting machine while another component of said 95 signal effects the transfer of adjustment from the normal to the normal and justification wedges acting in conjunction, and its punch acts upon the line measuring mechanism to record the value of an unjustified space, usually four units of the set. 100

The transfer mechanism of the casting machine responding to the transfer component of the space signal, is so constructed that it effects a change in the value of the normal wedge when combined with the justification wedges, while the dimensioning component of said signal controls the direct adjustment of the normal wedge, hence, pro- 105

vision is made in the record strip composing machine, whereby the punch producing said transfer component of the space signal through a connection with the line measuring mechanism shall register the value of the space at a fixed amount, say four units. In other words, for any given position of the normal wedge the dimension indicated is two units less when controlled by the dimensioning interponent of the space signal than when controlled by the like component of a non-justifying or type signal, and as the same punch may be used for producing the dimensioning components of both kinds of signals, type and space, special provision is made whereby the register on the line measuring mechanism will be two units less when used for a justification space signal than when used for a non-justifying type signal.

Now, the object of the present invention is to enable the justification fraction for a line to be applied to any one or more of the normally non-justifiable types indicated therein in the record strip, and this is accomplished by providing controllable means for coupling up all or any of the dimension indicating punches with the punch producing the transfer component of the space signal, and at the same time cutting out the connection between the transfer punch and the line measuring mechanism, so that the value of the indicated and otherwise non-justifiable type will be registered thereon instead of the value of the justifying space, to the end that the transfer component of the justification space signal may be added to the signal of the otherwise non-justifiable type signal and the normal value of said type signal be registered on the line measuring mechanism.

The addition of the transfer component to the otherwise non-justifiable type signal has the effect, in the casting machine, of transferring the produced adjustment of the mold from the normal to the normal plus justifying adjusting device, and as this diminishes the value of the indicated type two units, the deficiency is made up and applied through the medium of the justification signal, the value of the latter being increased two units of the set which amount is thus added to each of the normally non-justifiable type signals to which the transfer component has been applied, in other words, the shortage in the indicated measure resulting from the operation of the transfer mechanism is made good by a corresponding increase in the value of the justification signals.

In the accompanying drawings illustrating a preferred form of embodiment of the invention, Figure 1 is a front elevation partly in section of a keyboard composing machine showing the improvements applied

thereto. Fig. 2 is an end elevation partly in section. Fig. 3 is a top plan view and Fig. 4 a vertical section of a portion of the permutation mechanism intermediate the keys and punches through which the latter are controlled. Fig. 5 is a sectional view of the cut out for the line measuring mechanism and the control valve therefor. Fig. 6 is a detached perspective of the additions made to the commercial composing machine for embodying the improvements therein. Fig. 7 is a sectional view of the cut out for the line measuring mechanism.

The same numerals designate like parts in the several figures.

The invention is illustrated in its application to the keyboard composing or perforating machine of Patent No. 944,405 hereinbefore referred to, and it will suffice for purposes of identification to designate some of the principal elements with which the improvements are more directly related such as the keys 1; the series of punches 2; the series of transmitting members 3 through one or more of which the movement of each key is communicated to one or more valve bars (not shown), each of the latter controlling the action of a punch; the line measuring and justification indicating mechanism 4; the paper feed 5; the series of levers 6 through which the dimensioning punches of series 2 operate upon the admeasuring devices of the line measuring mechanism; the stop-bars 7 and the lever 8 through which the punch of the transfer component of the space signal actuates the four unit stop bar of the admeasuring mechanism.

By reference to the prior patent it will be found that each key 1 exercises control over one or more of the punches 2 in the production of the signal appropriated thereto, whether it be a type, space, justification or other signal; and that in so controlling the punches it oscillates one or more of the transmitting members 3, of the latter coupled with the dimensioning punches, and that the punch for the transfer component of the space signal, represented by transmitting member 3^x, is coupled through lever 8 with the first or four unit member of the stop bars 7.

In carrying out the present invention controllable means are supplied for coupling the several dimensioning punches with the transfer punch so that the type signal produced shall have the transfer signal component added thereto and to preserve the normal relation existing between said dimensioning punches and the line measuring mechanism so that the normal values of said punches will be registered instead of the value of the transfer punch, means are provided for automatically uncoupling or rendering inactive the connection between

the transfer punch and the admeasuring member of the line measuring mechanism controlled thereby. These functions are performed by the mechanism about to be described.

5 Suitably supported and guided upon the frame in proximity to the several transmitters 3, 3^x, is arranged a laterally and longitudinally movable bar or interponent 10, Figs. 1, 2, 3 and 4, provided with a shoulder 11 in position to engage and operate upon the transmitter 3^x of the transfer punch, and with a series of shoulders 12 in position to engage and be separately operated upon by each of the several dimensioning punch transmitters 3, when said interponent is advanced into the paths of the latter. Conveniently interponent 10 is constructed in the form of a lever pivotally 10 connected to the frame at one end by a slip joint 12^x and suitably guided at the opposite or free end, and to said lever is connected an actuator, in the form of bell crank lever 13, one arm whereof is coupled by a slip joint 25 with lever 10 and the opposite arm, playing between stops 14, provided with motor controlled devices represented by a piston 15 working in cylinder 16 in opposition to a retracting spring 17. Until the motor controlled devices are energized by the admission of pressure in cylinder 16, interponent 10 is held in disengaged position and the normal operation of the machine as a whole is unchanged; but upon the admission of pressure 30 to said cylinder interponent 10 is advanced to its active position where the motion of any one of the dimensioning punch transmitters 3 during the production of a type signal will be communicated to transmitter 3^x to add the transfer component of the space signal to the designating and dimensioning components of the produced type signal. Under these conditions and in the absence of competent means to counter- 35 act or prevent it, the value of the produced signal as registered on the line measuring mechanism would be that of the space signal, *i. e.*, four units, instead of that of the type indicated, owing to the fact that the 40 first or four unit stop bar is coupled with the transfer punch and to provide for this contingency and render the normal admeasuring devices operative to register the value of the produced type signal means are supplied for automatically cutting out or rendering inoperative the lever through which the transfer punch is normally coupled with the admeasuring devices. With these ends in view said lever 8 is provided with a removable fulcrum represented by a piston or bolt 45 50 55 60 65 70 75 80 85 90 95 100 105 110 115 120 125 130 135 140 145 150 155 160 165 170 10775

equipped with a series of punches including a transfer and a plurality of dimension indicating members, a series of keys controlling said punches, and a line measuring mechanism provided with admeasuring means controlled by said transfer and dimension indicating members, and in combination therewith, controllable means for simultaneously rendering inoperative the connection between said transfer member and the line measuring mechanism and coupling up for action said transfer and dimensioning members.

3. In a record strip composing machine, the combination of the following elements, to-wit: a series of key-controlled punches including a transfer member, a line measuring mechanism whose admeasuring members are coupled to respond to the several keys including that of the transfer member, to register the individual values thereof; and controllable means for cutting out the admeasuring member of said transfer member.

25 4. In a record strip composing machine, the combination of the following elements, to-wit: a series of type and space indicating keys; a series of punches responding singly or in multiple to said keys including a transfer indicating punch; a line measuring mechanism provided with admeasuring members coupled with and responding to said keys to register the values of the signals represented thereby; and controllable means for temporarily suspending the action of the admeasuring member for the transfer punch and for coupling the latter with the type keys so that the signal produced by any type key will include the transfer component and the value of the type indicated by said key will be registered.

5. In a record strip composing machine such as described provided with a series of punches including a transfer punch, and type and space indicating keys controlling said punches singly or in multiple through a series of transmitters, to produce distinctive signals, and in combination therewith, controllable means for temporarily coupling the transmitter for the transfer punch with the other transmitters so that the type keys when operated will add a transfer component to the produced type signal.

6. In a record strip composing machine such as described and in combination with the transmitters of the transfer and dimensioning punches thereof, a movable interponent adapted to temporarily couple the transmitters of the dimensioning punches with that of the transfer punch in a manner to permit individual action thereon.

7. In a record strip composing machine such as described and in combination with the transfer and dimensioning punches, and the actuating levers through which said

punches are coupled with the admeasuring members of the line measuring mechanism thereof, controllable means for temporarily rendering inoperative the actuating lever coupled with the transfer punch so that the latter may coöperate in the production of a type signal containing a transfer component without at the same time affecting the line measuring mechanism.

8. In a record strip composing machine such as described provided with a series of key-controlled punches including a transfer punch and a plurality of dimensioning punches, and a line measuring mechanism provided with admeasuring devices individually controlled by said transfer and dimensioning punches, and in combination therewith, an interponent adapted to couple the individual dimensioning punches with the transfer punch and uncoupling means for the admeasuring member of said transfer punch, whereby a transfer component may be added to any type signal and the value of the latter registered by the line measuring mechanism.

9. A record strip composing machine equipped with a series of key controlled punches including a transfer punch and a plurality of dimensioning punches, and a line measuring mechanism whose admeasuring devices are coupled with said punches to register the value of each, and in combination therewith, a motor-actuated means for coupling the transfer punch with any dimensioning punch so as to cause it to operate in conjunction therewith, and a motor-controlled means for rendering the transfer punch inoperative upon the line measuring mechanism.

10. A record strip composing machine equipped with a series of key-controlled punches including a transfer punch and a plurality of dimensioning punches, and a line measuring mechanism whose admeasuring members are separably and individually controlled by said transfer and dimensioning punches, and in combination therewith, a motor-controlled means for cutting out or suspending the action of the admeasuring member responding to the transfer punch, a motor-controlled means for coupling the transfer punch with each dimensioning punch to cause them to operate together, and means for simultaneously energizing the motors of said cutting out and coupling means.

11. In a record strip composing machine equipped with a series of punches including a transfer punch and a plurality of dimensioning punches, a series of keys and transmitters for actuating said punches singly or in multiple, and a line measuring mechanism separately controlled by said transfer and dimensioning punches, and in combination therewith, means for coupling the transfer

and dimensioning punches, a motor for said coupling means, means for uncoupling the transfer punch from the line measuring mechanism, a motor for said uncoupling means, and a control device common to the two motors.

12. In a record strip composing machine such as described the combination with the lever connecting the transfer punch and line measuring mechanism, of a movable fulcrum for said lever coupled with a piston and spring for shifting said fulcrum to alternately support and release said lever.

13. In a record strip composing machine

such as described and in combination with 15 the series of transmitting members through which the keys exercise control over the punches, of a movable interponent adapted to couple one of said transmitting members with a plurality of the remaining members, 20 and a motor for controlling the position of said interponent.
